DESIGN FOR A SCORE CARD

Harry J. Le Roy, Hammond, Ind.

Application August 25, 1934, Serial No. 53,071

Term of patent 7 years

To all whom it may concern:

Be it known that I, Harry J. Le Roy, a citizen of the United States, residing at Hammond, in the county of Lake and State of Indiana, have invented a new, original, and ornamental Design for Score Cards, of which the following is a specification, reference being had to the accompanying drawing, forming part thereof.

Figure 1 is a perspective view of the score card in closed or folded position;

I claim:

The ornamental design for a score card substantially as shown.

HARRY J. LE ROY.
